PIVOTED MEANS FOR DIRECTING DRYING GAS INTO THE INTERIOR OF HOLLOW ARTICLES

Harry D. Lathrop, Chicago, Ill., assignor to The Lathrop-Paulson Company, Chicago, Ill., a corporation of Illinois

Application September 11, 1943, Serial No. 501,948

3 Claims. (Cl. 34—105)

1

This invention relates to an air jet and the like, and more particularly to a device for discharging air or other gas into the interior of a can as the can is advanced in can washing apparatus.

An object of the invention is to provide an air jet for discharging air into the interior of a can to dry the surface of the can as the can is automatically advanced through can washing apparatus and equipment. Another object is to provide a discharge tube for passing air into the interior of the can which is automatically moved into and from the interior of the can as the can is advanced along a predetermined path in the can washing apparatus. Still another object is to provide in can washing equipment, an air jet which is automatically raised and lowered as a can is passed in inverted position through the equipment so that air or other drying medium may be discharged upwardly into the interior of the can to dry the same without interfering with the movement of the can through the apparatus. A further object is to provide a pivotally or swingably mounted casing, together with a counterweight which balances the casing and disposes the casing in the path of a can in the can washing apparatus so that the casing is engaged by the can passing therethrough to swing the casing downwardly out of the path of the can and, in combination, a conduit for introducing air or other drying medium into the discharge casing.

Other features and advantages will appear from the specification and drawing, in which—

Fig. 1 is an elevational view, partly broken away, showing a can supported in the washing apparatus and the jet in position to discharge the drying medium into the interior of the can; Fig. 2 is a perspective view of the discharge jet; and Fig. 3 is a vertical sectional view, partly in elevation, showing the discharge jet mounted upon the air conduit which communicates therewith.

The present invention contemplates an automatically-operated discharge tube or jet which is, in effect, self-rising in that it is swung into the interior of the mouth and neck of a can when the can in the can washing apparatus passes over the discharge tube. The discharge tube or jet thus does not interfere with the movement of the can through the apparatus, but at the same time provides effective introduction of air or other drying medium into the interior of the can. In this manner, cans which have been washed in the equipment are readily dried by the flow of air therethrough.

2

In the embodiment of the invention described herein, a can 10 having a neck 11 and a wide open mouth 12 is supported in inverted position upon a chain 13 or other suitable track which provides a predetermined path for the passage of the can through the can washing equipment. A dog or lug 14 engages the rim 15 of the mouth of the can so as to move the can along the predetermined path within the washing equipment.

10. The can washing equipment or apparatus may be of any suitable or conventional type and the portions shown are intended to illustrate a portion of such apparatus in which a can is automatically advanced step by step through the can washing apparatus. Instead of the chain 13, any suitable type of track may be used to support the can 10 in inverted position.

20. A tubular casing 16 is pivotally supported by the pivot pin 17 at the lower portion thereof, a mounting being disposed below the path for the movement of the can above the chain or track 13. The casing 16 may be of any suitable shape or construction and may be circular or polygonal in cross section as well as in the shape illustrated.

25. The casing should, however, be tubular in order to provide a passage for the drying medium which may extend into the can 10.

As seen particularly in Fig. 2, the discharge casing 16 may be provided with a counterweight 18 extending downwardly below the portion of the casing at which the casing is pivotally supported. The counterweight may be secured to the wall 19 of the casing by attachment of the extension 20 of the counterweight to such wall.

35. The opposed side walls 21 and 22 of the casing may be equipped with registering apertures 23 and 24 through which the pivot pins 17 are passed in mounting the casing. The wall 25 of the casing 16 is preferably cut away at the lower portion thereof so as to permit the casing to be swung downwardly about its pivot without engagement with the air conduit 26 which communicates with the lower portion of the casing. The swingable or pivotal movement of the casing is illustrated in Fig. 3 in which the casing is shown in dotted lines in lower position.

40. Any suitable means (not shown) may be used for supporting the pivot pins 17 upon which the casing in turn is supported. If desired, a bracket 17a may be clamped upon the upper end of conduit pipe 26 and have an extension for receiving the pivot pin 17, as shown in Fig. 3.

45. The casing 16 is preferably tapered slightly inwardly toward the upper or discharge end there-

of, and in cross section dimensions should be substantially smaller than the neck 11 and mouth 12 of the can into which it is introduced. The length of the casing should be sufficient to permit the casing to extend upwardly, when in vertical position, into the interior of the can, preferably as shown to a portion of the can at or slightly beyond the neck thereof. With this construction and arrangement, ample space is provided about the outer periphery of the casing to permit air which is being discharged from the can to move downwardly and outwardly between the neck and mouth of the can and the casing therein. This provides for a free circulation of air or other drying medium in that the air is discharged upwardly at relatively high velocity into the central portion of the can and flows downwardly along the walls thereof and out through the neck and mouth of the can about the outside of the casing.

Preferably, the air conduit 26 which communicates with the lower portion of the casing is of cross section dimensions somewhat smaller than the casing and extends upwardly into the casing so that the lower portions of the walls of the casing overlap the air conduit 26.

In operation, the discharge jet or casing 16 swings about a horizontal axis provided by the pivot 17 so that the casing 16 moves in a vertical plane passing through the path along which the can is moved. Thus, the casing moves forwardly and rearwardly along the path of the can as it moves upwardly and downwardly to and from discharge position. In upper or vertical position, the casing extends upwardly into the open mouth and neck of the can, and the air which may be passed at high velocity from the air conduit 26 to the casing 16 is introduced into the central portion of the can. The air flows upwardly into the central portion of the can and downwardly along the walls of the can and downwardly and outwardly from the can through the portions of the neck and mouth about the outside of the casing.

In lower or substantially horizontal position, as indicated in dotted lines in Fig. 3, the casing has been swung downwardly out of the path of the can so that the can may move freely through the washing apparatus without interference by the casing.

As the can is automatically advanced along the path provided by the chain or track 13 and in the direction of the arrow shown in Fig. 1, it approaches the casing 16 and the forward edge of the rim 15 engages the rear wall 19 of the casing. The casing is swung forwardly and downwardly about the pivots 17 to the position shown in dotted lines in Fig. 3. The forward side of the mouth 12 and neck 11 of the can 10 then passes over the casing and the casing swings upwardly to the position shown in Fig. 1 within the mouth and neck of the can. Air is discharged upwardly into the can until the can is dried. The can is then again advanced in the direction of the arrow in Fig. 1, and the rear wall of the neck 11 and mouth 12 of the can engages the wall 19 of the casing to swing the casing forwardly and downwardly to permit the can to pass thereover. The operation is repeated with the next can passing through the apparatus.

If desired, the counterweight 18 may be almost evenly balanced with the portion of the casing 16 above the pivots 17. In this case, the casing 16 is swing upwardly to vertical position by the combined effect of the counterweight 18 and the

blast of air which is passed upwardly from the end of the air conduit 26.

By reason of the high velocity which is preferably imparted to the air passing through the discharge casing 16 and the smaller dimensions of the air conduit 26 than those of the casing 16, substantially no air escapes through the cutaway portion of the wall 25 of the casing 16. At the same time, this cutaway portion permits the swingable movement of the casing.

Although air will normally be used, any suitable gaseous medium may be passed through the discharge jet or casing. If desired, the air may be heated so as to increase its effectiveness as a drying medium.

Although the invention has been described in connection with a specific embodiment, it will be apparent that many modifications and changes may be made without departing from the spirit and scope of the invention.

I claim:

1. In apparatus for drying cans wherein a can in inverted position is advanced along a predetermined path, a device for discharging a gaseous medium into the interior of the can comprising a tubular casing, a horizontally-disposed pivot below said path for supporting the casing at the lower portion thereof for pivotal movement about a horizontal axis, means for supporting the pivot, counterweight means carried by said casing extending downwardly below said pivot to at least balance the weight of the portion of the casing above said pivot, a conduit having an outlet opening extending upwardly into the lower end of the casing for introducing a gaseous medium into the casing under relatively high velocity, said casing being swingable about said pivot between upper position wherein the casing extends upwardly into the interior of a can disposed thereabove in said predetermined path and lower position wherein the casing is withdrawn from the interior of the can and extends across said outlet to substantially close the same, the cross section dimensions of the casing being substantially greater than the cross section dimensions of the outlet of the conduit and the casing forming in upper position a continuation of the conduit, said casing being cut away at one wall to permit the casing to swing downwardly to lower position without interference from said conduit, the casing being moved from upper position to lower position by engagement with the advancing can and being moved from lower position to upper position by the counterweight and the upward pressure exerted on the upper portion of the casing and by the gaseous medium in said conduit when the casing is in lower position.

2. In apparatus for drying cans wherein a can in inverted position is advanced along a predetermined path, a device for discharging a gaseous medium into the interior of the can comprising a tubular casing, a conduit having an outlet adjacent said tubular casing for discharging a gaseous medium into said tubular casing, means disposed below said path for supporting said casing at the lower portion thereof for pivotal movement about a horizontal axis, counterweight means carried by said casing extending downwardly below said supporting means to at least balance the weight of the portion of the casing above said supporting means, said outlet communicating with the interior of said casing, said casing being swingable between upper position wherein the casing extends upwardly into the interior of a can disposed thereabove in said predetermined

path and gaseous medium flows upwardly through said outlet and said casing into the can and lower position wherein the casing is withdrawn from the interior of the can and extends across said outlet to substantially close the same, the gaseous medium in said outlet exerting an upward pressure on the upper portion of the casing when the casing is in lower position, said casing being moved from upper position to lower position by engagement with the advancing can.

3. In apparatus for drying cans wherein a can in inverted position is advanced along a predetermined path, a device for discharging a gaseous medium into the interior of the can comprising a tubular casing, a conduit having an outlet adjacent said tubular casing for discharging a gaseous medium into said tubular casing, means disposed below said path for supporting said casing at the lower portion thereof for pivotal movement about a horizontal axis, counterweight means carried by said casing extending downwardly below said supporting means to at least balance the weight of the portion of the casing above said supporting means, said outlet communicating with the interior of the casing, said casing being swingable between upper position wherein the casing extends upwardly into the in-

terior of a can disposed thereabove in said predetermined path and wherein the casing forms a continuation of said outlet whereby the gaseous medium flows upwardly through said outlet and casing into the interior of the can and lower position wherein the casing is withdrawn from the interior of the can and extends across said outlet to substantially close the same and wherein the gaseous medium in the outlet exerts an upward pressure on the upper portion of the casing, said casing being moved from upper position to lower position by engagement with the advancing can and having a wall cut away to permit the casing to swing downwardly to lower position without interference from said outlet.
